UNITED STATES PATENT OFFICE.

FREDERICK DEISER, OF CHICAGO, ILLINOIS, ASSIGNOR TO CHI-ILL-ELECTRIC COMPANY, OF CHICAGO, ILLINOIS, A CORPORATION OF ILLINOIS.

ELECTRIC PLUG.

1,106,442.

Specification of Letters Patent. Patented Aug. 11, 1914.

Application filed October 24, 1911. Serial No. 658,457.

To all whom it may concern:

Be it known that I, FREDERICK DEISER, a citizen of the United States, residing at Chicago, in the county of Cook and State of Illinois, have invented a new and useful Improvement in Electric Plugs, of which the following is a specification.

My invention relates, more particularly, to what are commonly termed "rotatable" socket-plugs formed of inner and outer relatively rotatable members, one of which is connected with a metal sleeve for screwing into the socket and forming one contact for the electrical circuit, and the other of which carries the contact for engagement with the other electrical contact of the socket and is connected with the wires leading from the plug. My object is to provide a novel and simple construction of so-called "rotatable" socket-plug which may be economically manufactured and which will permit the connections between the plug and the current-conducting wires to be made readily and quickly.

My invention is illustrated in the accompanying drawings, in which—

Figure 1 is a view in elevation of a socket plug constructed in accordance with my invention. Fig. 2 is an end view of that part 30 of the plug which enters the socket. Fig. 3 is an end view of the opposite end thereof. Fig. 4 is an enlarged section taken at the line 4 on Fig. 5 and viewed in the direction of the arrow. Fig. 5 is a section taken at the lines 5 on Figs. 1 and 4 and viewed in the direction of the arrow. Fig. 6 is a section taken at the line 6 on Fig. 4 and viewed in the direction of the arrow. Fig. 7 is a view in elevation of the outer, tubular, rotatable member of the plug. Figs. 8 and 9 are views in elevation of the two sections of the inner member of the plug. Figs. 10 and 11 are face views of the inner opposing faces of the sections shown in Figs. 8 and 9 respectively. Figs. 12 and 13 are perspective views of the co-operating contact-members for establishing electrical connection between one of the binding-posts on the plug and the metal threaded sleeve on the member of Fig. 7. Fig. 14 is a perspective view of the center contact carried by the inner plug-member of Figs. 8 and 9; and Fig. 15, a broken, sectional, view taken at the line 15 on Fig. 1, showing the shell and locking dog therefor.

My improved socket-plug, in its preferred

embodiment, comprises, generally stated, an outer tubular member, or bushing, 15 of insulating material, such as vulcanized rubber, or fiber; a threaded shell 16 of metal having an inwardly-extending flange 16^a on its inner end and adapted to be screwed upon the threaded end 17 of the bushing 15 and at which the plug screws into the threaded portion of a socket, as for example the usual electric-lamp socket (not shown); an inner contact-equipped member 18 of insulating material, as for example porcelain, to which the terminals of the wires leading to the plug are connected, as hereinafter described, and which is equipped with a contact for engaging with the other contact of the socket referred to; and means for electrically connecting the shell 16 to the respective wire-terminal.

The bushing 15 is provided at its outer open end with an inner annular flange 19 producing the restricted opening 20, and the screw-threaded portion 17 of the bushing 15 is longitudinally grooved, at opposite sides thereof, as represented at 21 and 22. The inner member 18 is formed of two separate semi-cylindrical sections 23 and 24. The inner surface of the section 23 contains a groove 25 which extends to the outer end of the section 23 and in which a metal-contact member 26 snugly fits. The member 26 is provided at its outer end with a lug 27 which extends beyond the outer end of the plug (Figs. 4 and 5), and forms its center electric contact for engagement with the center contact of the socket into which the plug is inserted when in use. The contact-member 26 is held in place by screws 28 and 28^a which screw into threaded openings 28^b and 28^c, respectively, in the section 23, the screw 28 forming a binding-post for one of the electric wires (not shown) of the plug, it being preferred that the section 23 be formed, on its inner face, with a pair of spaced ribs 29 and 30 extending on opposite sides of the inner end of the member 26, as represented.

The outer ends of the sections 23 and 24 are peripherally flanged as represented at 31, the section 23 being recessed adjacent to the rib 30, as represented at 32, for receiving the depending section 33 of an arc-shaped member 34 of sheet-metal which fits, at its curved section 35, against the underside of the flange 31 on the section 23, a lug 36 on the section 33 fitting against the inner face of the sec-

110

tion 23 and receiving a screw 37 which screws into a threaded opening in the plug-section 23 and serves as a binding-post for the other of the plug-wires referred.

5 The flat, inner, face of the section 24 is grooved as represented in Fig. 10 to permit the ribs 29 and 30 and those parts connected with the section 23 which extend beyond its inner face, to fit within the section 24 and 10 permit the sections 23 and 24 to fit together without obstruction.

15 Fitting against the inner end of the bushing 15 is a ring 38 of metal, which is provided with strip-sections 39 and 40 extending at angles to the ring 38 and fitting, preferably under tension, into the grooves 21 and 22, respectively, the ring 38 thus being clamped to the bushing 15. The strip-section 39 contains a transverse notch 41 and 20 its extremity is deflected with relation to the other portion thereof in a direction away from the bushing 15 to form a spring-dog 42 which serves to engage with corrugations 43 on the inner edge of the shell 16 when 25 the latter is screwed to position on the bushing 15 and prevent the latter from unscrewing from the bushing until the dog 42 is released as by pressing it inwardly to release it from the engaged corrugation 43.

30 To assemble the parts of the plug, the wires (not shown) for connection with which to a socket the plug is used, are first inserted through the opening 20 in the bushing 15 and then connected, respectively, with 35 the binding posts 28 and 37. The sections 23 and 24 are then fitted flatwise together to the position illustrated in Fig. 5, and said wires positioned to lie within opposing curved grooves 44 in the opposed faces of 40 the sections 23 and 24 opening into recesses 46 in said sections, the grooves 44 preferably containing transversely-extending ribs 45 between which said wires are gripped when the sections 23 and 24 are forced together as 45 by means of a screw-bolt 47, which releasably holds these sections together and prevents the wires from becoming accidentally disconnected from the binding-posts. The member 18 is then introduced into the bushing 15 to 50 the position shown in Fig. 5 and the shell 16 then screwed tightly upon the bushing 15 to cause the spring-dog 42 to extend into one of the corrugations 43 and lock the shell 16 against turning relative to the bushing 15. 55 In this position of the shell 16 its flange 16* overlaps the outer face of the flange on the member 18 and thus serves to prevent accidental separation of the members 15 and 18.

60 When the plug is to be inserted into a socket to put it to use, the operator, grasping the bushing 15, screws it, at its shell 16, into the socket until the central contact 27 of the plug is forced into close engagement with the central contact of the socket. This 65 causes the arc-member 34 to be forced into

close contact with the ring 38, and as the ring 38 is in electrical contact with the shell 16, through the medium of the strip-section 39, which preferably contacts with the shell 16 substantially throughout the length of the former, a positive electrical connection between the shell 16 and binding-post 37 is effected. As the bushing 15 is free to rotate about the member 18 the plug screws into the socket without turning the member 18 and thus twisting of the wires connected therewith is avoided.

70 The parts of the plug may be disassembled with ease by springing the dog 42 inwardly, thereby unlocking the shell 16 and permitting it to be unscrewed from the bushing 15, whereupon the member 18 may be withdrawn from the bushing 15 and access be had to the interior thereof.

75 What I claim as new, and desire to secure by Letters Patent, is—

1. An electric plug comprising relatively rotatable members, a threaded metal shell screwed upon one of said members, electrical connections on the other of said members for electric wires, a contact on said last referred to member in circuit with one of said connections, means electrically connecting said shell with the other of said connections, and means on said shell operating when the latter is screwed into place to prevent said members from separating.

80 2. An electric plug comprising a member provided with electrical connections for electric wires, a contact on said member in circuit with one of said connections, an apertured member and embracing said first-named member, a threaded metal shell on said apertured member, and contacting metal members confined between said first-named member and said apertured member and in circuit, respectively, with the other of said connections and with said shell.

85 3. An electric plug comprising relatively rotatable members, electrical connections on one of said members for electric wires, a threaded metal shell on the other of said members and embracing the one of said members provided with said electrical connections, a contact on said last referred to member in circuit with one of said connections, and relatively movable contacting metal members one of which is connected with the other of said connections and the other of which engages with said shell, for 90 the purpose set forth.

95 4. An electric plug comprising relatively rotatable members, electrical connections on one of said members for electric wires, a threaded metal shell on the other of said members and embracing the one of said members provided with said electrical connections, a contact on said last referred to member in circuit with one of said connections, and metal contacting members on said 100

first-named members and confined between transversely opposing portions of the latter, said metal members being connected, respectively, with the other of said connections and with said metal shell.

5. An electric plug comprising relatively rotatable members having transversely-extending opposing surfaces, electrical connections on one of said members for electric wires, a threaded metal shell on the other of said members and embracing the one of said members provided with said electrical connections, a contact carried by said last referred to member and in circuit with one of said 10 connections, contacting curved metal members confined between the opposing surfaces of said first-named members and in circuit, respectively, with the other of said connections and with said shell, for the purpose set forth.

6. An electric plug comprising relatively rotatable members provided with transversely-disposed opposing surfaces, electrical connections on one of said members for electric wires, a threaded metal shell on the other of said members and embracing the one of said members provided with said electrical connections, a contact on said last referred to member in circuit with one of said 25 connections, contacting curved metal members connected, respectively, with said first referred to members and having sliding contact with each other, said metal members being electrically connected with the other 30 of said connections and with said shell, for the purpose set forth.

7. An electric plug comprising relatively rotatable members, electric connections on one of said members for electric wires, a contact on said last referred to member in circuit with one of said connections, a threaded metal shell on the other of said members, means electrically connecting said shell with the other of said connections, and 45 means, operating automatically for releasably locking said shell in position, for the purpose set forth.

8. An electric plug comprising relatively rotatable members, electrical connections on one of said members for electric wires, a contact on said last referred to member in circuit with one of said connections, a threaded metal shell on the other of said members, and relatively movable contacting metal 50 members, one of which is connected with the other of said connections and the other of which contacts with said shell and forms means for automatically locking the latter in position.

60 9. An electric plug comprising relatively rotatable members, electrical connections on one of said members for electric wires, a contact on said last referred to member in circuit with one of said connections, relatively 65 movable contacting metal members one of

which is connected with the other of said connections and the other of which is provided with a spring-dog, and a threaded metal shell screwing upon the other of said first-named members and provided with a 70 dog-engaging surface, for the purpose set forth.

10. An electric plug comprising relatively rotatable members one of which is formed of sections separable longitudinally, electrical connections for wires in the interior of said last referred to member and accessible upon separating the sections thereof, a contact carried by said last referred to member and in circuit with one of said last referred 75 to sections, a threaded metal shell on the other of said members, and means for electrically connecting said shell with the other of said connections, for the purpose set forth.

80 11. An electric plug comprising relatively rotatable members, one of which is formed of longitudinally opposing sections, a contact on one of said sections provided with means for connecting a wire in circuit therewith, a metal member carried by said sectional member and provided with means for electrically connecting the other of the wires thereto, a threaded metal shell on the other of said first-named members, and a metal 85 member carried by said shell-equipped member and engaging with said first-named metal member and in circuit with said shell, for the purpose set forth.

12. In an electric plug, the combination of 100 relatively rotatable members, one of which is formed of longitudinally-opposing separable sections containing opposed curved grooves opening through an end of said member, binding posts for electric wires located on said last referred to member at the inner ends of said grooves, whereby wires introduced into said last referred to member and connected with said binding-posts will lie within said opposing grooves, and 105 means for forcing said sections together for gripping the wires in said grooves, for the purpose set forth.

13. In an electric plug, the combination of 110 relatively rotatable members, one of which is formed of longitudinally-opposing separable sections containing opposed curved grooves provided with projections and opening through the end of said member, binding-posts for electric wires located on said last referred to member at the inner ends of said grooves, whereby wires introduced into said last referred to member and connected with said binding-posts will lie within said opposing grooves, and means for 115 forcing said sections together for gripping the wires between said projections, for the purpose set forth.

14. In an electric plug, the combination of 120 relatively rotatable members one of which 125

4

is formed of longitudinally-opposing separable sections containing opposed grooves which open through an end of said member, binding posts for electric wires on said 5 last referred to member at the inner ends of said grooves, whereby the wires connected with said binding posts lie within said grooves, and means for holding said sections together and gripping the wires between 10 said projections, for the purpose set forth.

15. An electric plug comprising relatively rotatable members, electrical connections on one of said members for electric wires, contacts carried by said plug and in circuit respectively with said connections, one of said contacts being in the form of a shell carried by the other of said members, and means on 20 said shell for preventing said members from separating.

16. An electric plug comprising relatively rotatable members, electrical connections on one of said members for electric wires, a contact on said last referred to member in 25 circuit with one of said connections, a

threaded metal shell screwed upon the other of said members, relatively movable contacting metal members one of which is connected with the other of said connections and the other of which contacts with said shell and forms means for locking the latter in place, and means for holding said members in place, for the purpose set forth. 30

17. An electric plug comprising a member provided with electrical connections for 35 electric wires, a contact on said member in circuit with one of said connections, an apertured member, a metal member connected with the other of said connections and terminating in a spring finger extending longitudinally of said first-named member, and a threaded metal shell for holding said first-named and said apertured members together and provided with a shouldered portion for engaging with said 40 finger, for the purpose set forth. 45
